MARCEL IRON

Elias Clein, Brooklyn, N. Y.

Application April 21, 1936, Serial No. 75,643

3 Claims. (Cl. 132—37)

This invention relates to hair waving and curling irons of the type known as "Marcel irons" and has reference particularly to improvements in the pivoted arrangements connecting the tongs of such irons.

Curling irons of this character are usually constructed with a fixed pivotal connection between the tongs, which necessarily assume an angular position relative only to each other when engaged over the strands of hair to be waved and curled, and which cannot function with equal pressure throughout their effective length, because the angle of the tongs in clamped position is determined by the thickest portion of the hair being engaged and any less heavy strands on opposite sides of the thick portion are either entirely free of the effective pressure of the tongs or are so lightly engaged that only a very weak wave or curl is produced.

With the foregoing in mind it is the purpose of the present invention to overcome this fault and to utilize an automatically adjustable pivotal connection between the tongs, whereby the operation of clamping the latter upon the hair automatically moves the tongs into substantially parallel positions relative to each side of the strand of hair being engaged and enables the operator to evenly distribute the pressure of the tongs throughout their effective length.

One embodiment of my invention is described in the following specification, set forth in the appended claims and illustratively exemplified in the accompanying drawing, in which

Figure 1 is a substantially longitudinal sectional view of a curling iron showing the mandrel and clamping member in normal closed position;

Figure 2 is a side elevational view of the iron showing the pivotal connection between the tongs so adjusted as to increase the clamping and effective length of the iron;

Figure 3 is a substantially transverse sectional view of the pivotal connection taken on lines 3—3 of Figure 1.

Referring to the drawing, the curling iron comprises a pair of tongs, one thereof being a solid, cylindrical metal rod or mandrel 10, the outer end of which is beveled in the approved manner, while the mid-portion is flattened and joins an offset handle or grip 11. The flattened portion 50 is designated 12 and is provided with a rectangularly shaped slot 13, the major axis of which is disposed transversely of the longitudinal axis of the mandrel. Arranged in the slot 13 is a helical spring 14, one end thereof abutting 55 the end of the slot and the other end engaging

a block 15 slidably carried in the slot. The side of the block 15 facing the adjacent end of the slot 13 is grooved transversely thereof to loosely embrace the mid-portion of a pivot pin 16.

The pivot pin 16 is carried by the other tong which is a clamping member 17 and consists of a semi-cylindrical length of metal adapted to embrace the mandrel 10, a divided mid-portion between the spaced walls 18 of which the flattened portion 12 is disposed, and an offset handle 19. The handle 19 is arranged opposite the other handle 11 and the pin 16 is fixed at its ends in the spaced walls 18.

To assemble the curling iron the spring 14 and block 15 are placed in the slot 13 and the mandrel end 10 of the tong is inserted in the semi-cylindrical portion of the clamping member 17 where openings 20 in the walls 18 are aligned with the groove in the block 15. The pivot pin 16 is then inserted in the passage and upset at its ends. It should be noted that the axis of the pin 16 is not disposed in the longitudinal axis of the clamping member but is arranged on the side of the latter axis opposite that occupied by the other spring 14.

In operation, the grips 11 and 19 are separated and the mandrel 10 and clamping member 17 move apart at an angle having its initial apex in the axis of the pivot pin 16.

The hair to be waved is placed about the mandrel and the clamping member is brought down upon the hair by gripping the handles and exerting pressure to bring them together. Ordinarily the clamping action would cease when the hair is brought into contact with the clamping member, but in accordance with the present invention, continued movement of the handles towards each other is possible in order to increase the clamping pressure between mandrel and clamping member.

Beyond the point where the clamping member and mandrel are substantially coaxial in closed position, the block 15 begins to move automatically through the slot 13 and against the spring 14 until the clamping member and mandrel have accommodated themselves to the thickness of the hair throughout the length of the iron. The pressure then exerted upon the hair is substantially uniform over the entire effective length of the tongs.

What I claim is:

1. In a curling iron, the combination of a mandrel having a transversely slotted mid-portion and a clamping member having its mid-portion embracing the slotted mid-portion of the mandrel, a pivot pin carried by the clamping member

and projecting through said slot, and a spring in the slot to exert yieldable pressure against the pin.

2. In a curling iron, the combination of a mandrel having a transversely slotted mid-portion and a clamping member embracing the mandrel at its mid-portion and having a grip opposite the first grip, a pivot pin carried by the clamping member and disposed loosely in the slot of the mandrel, a block movable in said slot and engaging the pin, and a spring in the slot to exert yieldable pressure against said block.

3. In a curling iron, the combination of a mandrel having a transversely slotted mid-portion and a clamping member having its mid-portion embracing the slotted mid-portion of the mandrel, a pivot pin carried by the clamping member and projecting through said slot, a block movable in said slot to exert yieldable pressure against said block, the latter being grooved transversely to loosely embrace the pivot pin and to form a floating bearing for the same. 5

ELIAS CLEIN.
